UNITED STATES PATENT OFFICE.

WILLIAM L. SULLIVAN, OF FERGUSON, MISSOURI.

TICKET-ISSUING MACHINE.

1,308,966.

Specification of Letters Patent.

Patented July 8, 1919.

Application filed July 29, 1912. Serial No. 712,113.

To all whom it may concern:

Be it known that I, WILLIAM L. SULLIVAN, a citizen of the United States, residing at Ferguson, Missouri, have invented a certain new and useful Improvement in Ticket-Issuing Machines, of which the following is a full, clear, and exact description, such as will enable others skilled in the art to which it appertains to make and use the same.

10 This invention relates to ticket-issuing machines, and particularly to machines of the type that comprises means for feeding a continuous ticket-strip and severing it into lengths containing one or a plurality of tickets, the length of the severed strips being controlled by the operator who manipulates a certain device when two tickets are desired, a different device when three tickets are desired, etc.

20 The machines of this type which are now in general use require two separate and distinct operations each time several tickets are issued, one operation being the manipulation of the device that determines the length

25 of the severed strip or the number of tickets that are issued, and the other being the operation of the foot-treadle which constitutes the primary actuating mechanism of the machine. When only one ticket is desired the operator merely presses the foot-treadle once. One objectionable feature of machines of the type referred to is that the operator has to press the foot-treadle each time a ticket is issued and also actuate a hand-controlled device when two or more tickets are issued.

Another objectionable feature is that if the operator fails to release the foot-treadle the knife or movable cutter of the ticket-strip cutting mechanism remains open until the treadle is released, and during this time the purchaser is apt to grab the issued ticket or tickets which are still attached to the ticket strip and thus give the ticket strip a sudden jerk which causes it to break. Whenever this occurs a great deal of time is wasted in removing the mutilated ticket strip and restoring the machine to normal condition.

30 And still another objectionable feature of such machines is that the operator is apt to actuate the foot-treadle so vigorously that the ticket strip or some of the elements

of the machine break, thus requiring the services of a machinist quite frequently to 55 keep the machine in workable condition.

One object of my invention is to provide a motor-operated ticket-issuing machine which is so constructed that the parts of the machine will be actuated with a uniform pressure at each cycle of operations.

Another object is to provide an inexpensive ticket-issuing machine of simple design that is not liable to get out of order and which is so constructed that the issued portion of the ticket strip will be severed automatically before the purchaser has an opportunity to grab same and thus tear the ticket strip.

And still another object is to provide a 70 ticket-issuing machine in which the ticket strip feeding mechanism is so designed that the ticket strip will not be subjected to strains during the operation of feeding same. Other objects and desirable features 75 of my invention will be hereinafter pointed out.

Briefly described, my improved ticket-issuing machine consists of a feed wheel that feeds the ticket strip forwardly to the 80 point where the tickets are issued, means for severing the ticket strip into short lengths containing one or a plurality of tickets, means under control of the operator for determining the degree of movement of 85 said feed wheel so as to regulate the number of tickets that are issued, and a motor of some suitable type that forms the primary actuating mechanism of the machine either to operate the feed wheel or to store up 90 energy in a spring that operates the feed wheel. The mechanism that imparts movement to the ticket strip feed wheel comprises a feed shaft provided with a toothed member that meshes with a coöperating 95 toothed actuating member such, for example, as a sprocket-chain, a spring connected to said sprocket-chain for moving it in one direction, and motor-driven means for moving said sprocket-chain in the reverse direction so as to store up energy in said spring. The machine is provided with a plurality of key levers or other suitable devices under control of the operator for setting up stops that govern the degree of movement of said 100 feed shaft, and a locking mechanism is pro-

vided for locking the feed shaft so as to normally hold it at rest, said locking mechanism being tripped or released automatically whenever one of the key levers 5 is actuated.

In the embodiment of my invention herein shown, the spring previously referred to is employed for rotating the feed shaft forwardly, and the motor-driven means that 10 stores up energy in said spring is utilized for rotating the feed shaft in a reverse direction, but I do not wish it to be understood that my invention is limited to such a construction for various changes could be 15 made in the design and arrangement of the coöperating elements of the machine without departing from the spirit of my invention.

Figure 1 is a side elevational view of the 20 machine;

Fig. 2 is a vertical longitudinal sectional view of the machine, said view being taken on approximately the line 2—2 of Fig. 11;

Fig. 3 is a top plan view of the machine; 25 Fig. 4 is a view similar to Fig. 2 showing the parts in a different position;

Fig. 5 is a horizontal sectional view taken on approximately the line 5—5 of Fig. 4 looking in the direction indicated by the 30 arrows;

Figs. 6, 7 and 8 are detail views of one of the stops that limit the movement of the feed wheel;

Fig. 9 is a side elevational view of the opposite side of the machine than that illustrated in Fig. 1, the right-hand side plate being broken away;

Fig. 10 is a horizontal sectional view taken on the line 10—10 of Fig. 9, looking in the 40 direction indicated by the arrows;

Fig. 11 is a rear elevational view of the machine;

Fig. 12 is a transverse vertical sectional view taken on the line 12—12 of Fig. 1;

45 Fig. 13 is a detail top plan view of the cutting mechanism;

Fig. 14 is a similar view showing the movable cutter or knife open;

Fig. 15 is a perspective view of the two 50 coöperating cutting members;

Fig. 16 is a vertical longitudinal sectional view taken on approximately the line 16—16 of Fig. 12, looking in the direction indicated by the arrows;

55 Fig. 17 is a similar view showing the parts in a different position;

Fig. 18 is a transverse sectional view taken on the line 18—18 of Fig. 16, looking in the direction indicated by the arrows;

60 Fig. 19 is a detail sectional view taken on the line 19—19 of Fig. 16;

Fig. 20 is a perspective view of one of the radially projecting pins on the feed wheel;

Fig. 21 is a perspective view of the feed- 65 wheel;

Fig. 22 is a perspective view of the star-wheel on the feed-shaft that coöperates with the pawl on the feed-wheel;

Fig. 23 is a perspective view of the device 70 that automatically locks the feed-wheel after the last ticket of the ticket strip has been issued;

Fig. 24 is a perspective view of the stationary ring that coöperates with the locking dog on the feed-wheel to prevent the 75 feed wheel from overthrowing;

Fig. 25 is a perspective view of the reciprocating bar to which one end of the feed shaft actuating chain is connected;

Fig. 26 is a perspective view of the motor- 80 actuated element that coöperates with said bar;

Fig. 27 is a perspective view of the sprocket-wheel of the feed shaft; and

Fig. 28 is a perspective view of the movable 85 contact member that causes the motor to become operative and inoperative automatically.

Referring to the drawings which illustrate the preferred form of my invention, A designates the counter of a ticket-booth underneath which my improved ticket-issuing machine is arranged, the casing of the machine comprising a top plate 1 which is preferably set flush with the top face of the counter A, 90 as shown in Figs. 1, 2 and 3. A continuous ticket strip α which is wound in the form of a roll B, is retained in position by means of a pivotally mounted arm 2 provided with a laterally projecting stub shaft 3, as shown 100 in Fig. 10 that projects into a spool 4 on which the ticket strip is wound, the arm 2 being preferably formed of resilient metal so as to enable the ticket strip roll to be arranged in operative position quickly and 105 easily. The inner end of the arm 2 is pivotally connected at 5 to a stationary part of the frame of the machine, and the ticket strip roll B is supported by a flanged roll 6 which may or may not be driven so as to 110 aid the feeding movement of the ticket strip.

The ticket strip α leads upwardly over a feed wheel C which is preferably provided with radially projecting pins 7 that coöperate with spaced holes in the ticket strip to 115 feed said strip forwardly through a slot 8 in the top plate 1 of the machine, as shown in Fig. 16. A shaft D, which I will refer to as the feed shaft or drive shaft of the machine, is connected with the feed wheel C 120 by means of a pawl and ratchet mechanism that I will hereinafter describe and which is so designed that the feed wheel will move forwardly when the shaft D rotates in one direction and will remain at rest when said 125 shaft rotates in the opposite direction. The feed shaft D is provided with a toothed member such, for example, as a sprocket-wheel 9 that meshes with a toothed actuating member that causes the feed shaft D to 130

rotate forwardly when said actuating member moves in one direction and rearwardly when said actuating member moves in the reverse direction. Said actuating member 5 preferably consists of a sprocket-chain 10 that passes over the sprocket-wheel 9, as shown in Fig. 1, and which is connected at its opposite ends to two separate and distinct means, one of which moves the chain 10 in 10 one direction, and the other means operating to move said chain in the opposite direction. One of said means preferably consists of a coiled contractile spring 11 connected at its upper end to the chain 10 and at its lower 15 end to a stationary bracket 12. The other means consists of a vertically disposed reciprocating bar 13 that is adjustably connected to the chain 10 by means of a threaded member 10^a which is screwed into the 20 upper end of the bar 13, as shown in Fig. 2. The bar 13 is moved downwardly or in a direction to store up energy in the spring 11 by means of a motor-actuated element 14 that engages the bar 13 at a certain period in 25 the cycle of operations of the machine, and which is released or disengaged automatically from the bar 13 after the spring 11 has been placed in tension and the drive shaft D locked. The motor-actuated element 14 here- 30 in shown consists of a vertically disposed bar arranged parallel to the bar 13 and having its lower end connected by means of a link 15 with a crank arm 16 on a shaft 17, the shaft 17 being provided with a pulley 18, 35 as shown in Fig. 1, that receives a belt 19 which passes over a pulley 20 on the shaft of a motor E of any suitable type, such, for example, as an electric motor. The bars 13 and 14 are guided vertically by means of 40 laterally projecting studs 21 on one of the vertically disposed partition plates 22 of the machine, said studs having heads that lap over the bars 13 and 14, as shown in Fig. 5. It is immaterial, however, what particu- 45 lar means is used for guiding the bars 13 and 14 as any suitable means could be used for this purpose. The motor-actuated member 14 reciprocates continuously when the motor E is in operation, and at a certain 50 period in the cycle of operations of the machine a laterally projecting hook 23 on the member 14 engages a coöperating movable hook or projection 24 on the bar 13, as shown in Fig. 4, and moves said bar 13 downwardly 55 so as to store up energy in the spring 11 and also rotate the feed shaft D in the reverse direction to that in which it moved during the preceding operation of the ticket strip feed wheel C. The means herein shown for 60 locking the feed shaft D consists of a bell-crank-shaped locking lever 25 pivotally mounted on a horizontal shaft 26 that extends under the top plate 1 of the machine, as shown in Fig. 2, and provided on its long 65 arm with a hook or catch 27 that coöperates

with a notch in a disk 28 that is rigidly connected to the feed shaft D, said locking lever 25 being acted upon by a coiled contractile spring 29 which normally draws the long arm of said lever toward the locking disk 28 70 on the feed shaft D.

The machine herein shown is so designed that it will issue one, two, three, four or five tickets; the number of tickets that is issued at each operation, of course, depending upon 75 the degree of movement imparted to the ticket strip π on the forward feeding movement of the feed wheel C. The means that I prefer to employ for controlling the forward feed movement of the feed wheel C 80 consists of a plurality of stops arranged in different horizontal planes adjacent the path of movement of the vertically reciprocating bar 13, and key levers for setting up said stops or arranging them in operative 85 position. Five key levers 30 are provided which are pivotally mounted on the cross shaft 26 that extends transversely of the machine under the top plate 1, each of said key levers having a finger-piece 31 that projects 90 upwardly through an opening in the top plate 1 of the machine. Four of said key levers are provided with arms 32 that project downwardly, as shown in Figs. 2, 4 and 11, and co-operate with a series of movable stops 33, 34, 35 95 and 36 that are arranged horizontally one above the other in a stationary guide member H secured to the partition plate 22. The arms 32 are arranged at one side of said stops, as shown in Fig. 11, and each of said arms is 100 provided with a laterally projecting extension that alines with one of the stops, one of the arms 32 having an extension 33^a that co-operates with the stop 33, one with an extension 34^a that co-operates with the stop 35, 105 and one with an extension 36^a that co-operates with the stop 36. The fifth key lever is provided with a depending arm 32^a, as shown in dotted lines in Fig. 4 and in full lines in Fig. 11, but this arm does not co- 110 operate with a stop as the only function it performs is to trip the locking lever 25. The stop which may be said to co-operate with this fifth key lever is a stationary stop and is designated by the reference character 37 115 in Figs. 2 and 4. When any one of the key levers 30 is depressed the arm 32 on said lever strikes against a horizontally disposed pin 38 on the short arm of the bell-crank-shaped locking lever 25 and thus raises the 120 long arm of said lever far enough to release the locking disk 28 on the driving shaft E, as shown in Fig. 4. If the key lever that is depressed is either the first, second, third or fourth key lever the stop that co-operates 125 with same will be projected forwardly into such a position that it will arrest the upward movement of the reciprocating bar 13 which moves upwardly under the influence of the spring 11 as soon as the feed shaft D 130

is released. As shown in Figs. 2, 4, 6, 7 and 8, each of the stops 33 to 36 is provided on its lower edge with a notch 39 and at its front end with a laterally projecting pin 40. 5 A coiled contractile spring 41 is connected to each of said stops in such a manner that it tends to draw the front end of the stop downwardly so that when the stop is moved forwardly the notch 39 in the lower edge of 10 same will catch on the edge of the opening in the guide member 37 through which the stop is projected, see Figs. 4 and 7. The pivotally mounted hook 24 on the bar 13 is substantially bell-crank-shaped, and the 15 short leg of same is provided with a laterally projecting tail 24^a, as shown in Fig. 25, that strikes against the stop which has been set up or arranged in operative position when the bar 13 moves upwardly, as shown in Fig. 20. The blow that the tail 24^a strikes said stop moves the front end of the stop upwardly far enough to disengage the notch 39 in the stop from the guiding member H, and a cam 13^a on the bar 13 then strikes the 25 front end of the stop and moves said stop rearwardly far enough to prevent the notch from reengaging with the member H when the bar 13 moves downwardly. In order to prevent the stop from moving rearwardly 30 out of alignment with the tail 24^a of the hook on the bar 13 I have provided the bar 13 with a clip 42 that has a laterally projecting flange 43, as shown in Fig. 25, which passes between the pin 40 on the stop and the portion of the guiding member H through 35 which the stop passes, as shown in Fig. 8, and thus prevents the stop from being completely retracted after the tail 24^a trips same. In other words, when 40 the rod 13 moves upwardly under the influence of the spring 11 the tail 24^a of the hook 24 on said bar strikes against the stop that has been moved into operative position by the depression of the key lever, and thus 45 causes the upward movement of the bar 13 and the forward feed movement of the feed shaft D to be arrested, the engagement of said tail with said stop releasing the stop from the guide member H but the laterally 50 projecting flange 43 on the clip 42 preventing the stop from moving rearwardly out of engagement with the tail 24^a. The hook-shaped catch 24 on the bar 13 swings forwardly when the tail 24^a strikes against 55 the stop that is set up, as shown in Fig. 4, and on the succeeding downward stroke of the motor-actuated member 14, the hook 23 on said member engages the catch 24 and thus moves the bar 13 downwardly back to 60 normal position, the hook 27 on the locking lever 25 dropping into the notch on the disk 28 with which it cooperates and thus locking the feed shaft D as soon as the bar 13 is depressed to its normal position. The catch 24 is normally held in engagement with a stop 44 on

said bar 13 by means of a spring 45 shown in Fig. 25, and the upper end of the bar 13 is notched out at 46, as shown in Fig. 25, so as to form a shoulder that cooperates with the tail 24^a on the hook 24 to limit the outward movement of the hook when said tail strikes against the stop that has been set up or arranged in operative position. The stops 33, 34, 35 and 36 are so arranged that they will arrest the movement of the feed-wheel-operating mechanism after one, two, three or four tickets, respectively, have been issued through the slot 8 in the top plate of the machine, and the stationary stop 37 is so arranged that it will arrest the movement of said mechanism after a section of the ticket strip containing five tickets has been issued. 70

The mechanism that I prefer to use for severing the ticket strip α into short lengths consists of a movable cutter 50 that is actuated by means of a rock arm 51 loosely mounted on the feed shaft D and moved in one direction by means of a coiled contractile spring 52 and in the opposite direction by means of a disk 53 on the feed shaft D that is provided with a lug 54 that strikes against a laterally projecting pin 55 on the rock arm 51, as shown in Fig. 12. This rock arm 51 is also utilized to automatically restore the key levers to their normally raised position, and in the preferred form of my invention, as herein shown, a link 51^a, shown in Figs. 2 and 4, is arranged between the rock arm 51 and the pin 38 on the locking lever 25 that extends transversely in front of the 100 depending arms on the key levers, one end of said link 51^a having an elongated slot 51^b, as shown in Fig. 2, that receives a projection on the rock arm 51 and the other end of the link being pivotally connected to the 105 pin 38. In order to obtain an efficient cutting mechanism that can be removed easily for sharpening or repair I employ a stationary cutting member 56 that cooperates with the movable cutting member 50 and 110 to which said movable cutting member is pivotally connected at one end by means of a pivot 57, as shown in Fig. 13, 14 and 15. Said cutting members are arranged under the top plate 1 of the machine, and they 115 are retained in position by means of screws or other suitable fastening devices 58 that clamp the stationary cutting member 56 to a stationary part of the frame of the machine. One convenient way of connecting the movable cutting member 50 to the cutter-actuating rock arm 51 is to provide the cutting member 50 with a reduced portion or extension 59 that fits in a bifurcated portion at the upper end of the rock arm 51. 125 as shown in Figs. 2 and 12. When the feed shaft D rotates forwardly after being released in the manner previously described, the spring 52 moves the upper end of the rock arm 51 forwardly and thus opens up 130

the cutting mechanism, as shown in Fig. 14, or, in other words moves the movable cutter 50 into such a position that the check strip can pass upwardly through the check strip 5 slot 8 in the top plate of the machine. During the reverse movement of the feed shaft D the lug 54 on the disk 53 on said feed shaft strikes against the laterally projecting pin 55 on the rock arm 51 and thus moves said 5 rock arm forwardly, thereby causing the co-operating cutting members 50 and 56 to sever the ticket strip. Whenever it becomes necessary to re-sharpen the cutting mechanism the operator removes the screws 58 so 10 as to release both cutting members which can then be taken out of the machine.

The pawl and ratchet mechanism, previously referred to, that I prefer to use for transmitting movement from the feed shaft 20 D to the ticket strip feed wheel C consists of a star-wheel or spur-wheel 60 on the feed shaft D that co-operates with a pawl 61 that is pivotally connected to one of the spokes of the feed-wheel C, as shown in Figs. 25 16 and 17. When the feed shaft D rotates forwardly in the direction indicated by the arrow in Fig. 16 one of the teeth of the star-wheel 60 engages the pawl 61 on the feed-wheel C and thus causes said wheel to rotate 30 forwardly with the feed shaft D, the pawl 61 being held in such a position that it will co-operate with the teeth of the star-wheel 60 by means of a spring 62. The feed-wheel C is prevented from overthrowing forwardly 35 after the feed shaft D has come to rest by means of a pivotally mounted locking dog 63 on the feed-wheel C that co-operates with a stationary locking plate 64 having notches 65, as shown in Figs. 16, 17 and 24, that are 40 adapted to receive a projection 63^a on the dog 63. The locking dog 63 is acted upon by a coiled spring 66 which exerts yielding pressure on said dog in such a manner that the projection 63^a rides into and out of the 45 notches 65 in the locking plate 64 during the rotation of the feed-wheel C, said dog and spring also acting to lock the feed-wheel C at the end of each feeding movement. In case the feed-wheel C should overthrow 50 slightly it will be restored automatically to the position at which it should have stopped by means of a depending tail 63^b on the locking dog 63 which is engaged by one of the teeth of the star-wheel 60 on the feed-shaft 55 during the reverse movement of said shaft. Preferably, a stationary guard 67 of approximately the same width as the ticket strip α , is arranged adjacent the feed-wheel C, as shown in Figs. 16 and 17, so as to 60 form a substantial support for the ticket strip during the time said strip is being acted upon by the radially projecting pins 7 on the feed-wheel, said guard having a longitudinally extending slot through which 65 said pins travel. The ticket strip is pre-

vented from moving off the guard 67 by means of a pair of plates 67^a that conform to the curvature of the guard, as shown in Fig. 9, and which co-operate with the guard to form an arc-shaped guideway for the 70 ticket strip. In order to obtain access to the ticket strip the segmental plates 67^a are connected to a removable cover plate 67^b that closes an opening in the top plate 1 of the machine, said cover plate resting on 75 flanges on the under side of the top plate 1 and being retained in position by means of a spring-actuated catch 67^c on the cover plate that projects under the top plate 1, as shown in Fig. 9. If desired, a spring-actuated stop 80 pawl 68 can be mounted on the stationary locking ring 64 in such a manner that a laterally projecting extension 68^a on the free end of said pawl will move into the path of projections or shoulders on the feed-wheel 85 C and thus prevent said wheel from rotating forwardly after the ticket strip α has been used up, the pawl 68 having a tooth 69, as shown in Figs. 16 and 17, which bears against the under side of the ticket strip and 90 thus normally holds the pawl in such a position that it will not interfere with the forward movement of the feed-wheel C. As soon as the last ticket has been issued the pawl 68 moves outwardly and thus prevents further movement of the feed-wheel C, a stationary guide plate 70 being provided for receiving the tooth 69 on said pawl when the pawl is in operative position.

Any suitable type of counting mechanism 100 may be used for recording the number of tickets that the machine issues, the counting mechanism 71 herein shown comprising a pinion 72 that meshes with an idler 73 that co-operates with a gear 74 which is fastened 105 to the feed-wheel C, as shown in Fig. 9.

The flanged roll 6 on which the ticket strip roll B rests is preferably driven by means of a belt 75 that passes over a pulley 76 on the feed shaft D, as shown in Fig. 1, so as to aid 110 the feed wheel C and thus take the strain off the holes in the ticket strip and also keep the ticket strip taut without liability of tearing same.

The motor E which operates the machine 115 can be allowed to run continuously, or, if desired, the machine may be provided with means for causing the motor to start automatically when one of the key levers is depressed, and to stop automatically after a 120 portion of the ticket strip has been issued. The machine herein shown is constructed in this manner and is provided with a switch G of any suitable type such, for example, as a knife-switch, that is arranged in the electric circuit that energizes the motor and in such a position on the frame of the machine that it can be controlled easily by the operator. A lever 77, which is pivotally mounted on a stationary part of the frame of the 125 130

machine, is provided with a bifurcated end that receives a pin 78 on the bar 13, as shown in Figs. 2 and 4. Fastened to said lever is a movable contact 79 that coöperates with a flexible conductor 80 to establish electrical connection between the two poles of the switch G when the handle 81 of the switch is open, as shown in Fig. 2. When the lever 77 is in the position shown in Fig. 2 no current will flow through the motor E because the circuit is broken. When the bar 13 moves upwardly, however, after one of the key levers has been depressed the pin 78 on said bar rocks the lever 77 and thus moves the contact 79 into engagement with one of the contacts of the switch, as shown in Fig. 4, thus completing the circuit through the flexible conductor 80 which is connected to the movable contact 79 and to the other stationary contact of the switch. On the return downward movement of the bar 13 the contact 79 is moved automatically away from its coöperating contact and thus the circuit is again broken. In case it is desired to have the motor run continuously the operator raises the handle 81 of the switch so as to close the switch and thus cut out the movable contact on the lever 77.

If it is desired to issue three tickets, for example, the operator depresses the finger-piece 31 of the third key lever, thereby causing the stop 35 to be projected forwardly, as shown in Fig. 4, and also causing the locking lever 25 to be raised far enough to release the disk 28 on the feed shaft D. As soon as said shaft has been released the spring 11 contracts and imparts movement to the chain 10 which passes over the sprocket-wheel 9 on the feed shaft, the rotary movement of the feed shaft being arrested as soon as the tail 24¹ of the hook 24 on the bar 13 strikes against the stop 35. When the shaft D rotates forwardly the star-wheel 60 thereon engages the pawl 61 on the feed-wheel C and thus moves said wheel forwardly a sufficient distance to issue three tickets through the ticket slot 8 in the top plate of the machine. The depression of the key lever caused the bar 13 to move upwardly and thus set the motor E in operation, thereby causing the member 14 to start to reciprocate. When the catch 23 on the member 14 engages the coöperating catch 24 on the member 13 the member 13 will be restored to normal position. The operation of restoring the bar 13 to normal position stores up energy in the spring 11, actuates the cutting mechanism and thus causes the ticket strip to be severed automatically, and also restores the depressed key lever to its normal elevated position, the cycle of operations being completed as soon as the locking lever 25 engages the notch 27 in the disk 28 on the drive shaft D.

65 The mechanism that actuates the feed

shaft D and also the stops that coöperate with said mechanism are arranged between the partition plate 22 and the lefthand side plate 22^a of the machine, as shown in Fig. 12, and the feed wheel C and the pawl and ratchet mechanism and other coöperating parts are arranged between the partition plate 22 and the righthand side plate 22^b of the machine. the stationary locking ring 64 that coöperates with the dog 63 on the feed wheel being supported by studs and spacers 64^c that project laterally from the partition plate 22.

A machine of the construction above-described is not apt to get out of order easily because the coöperating parts of the machine are actuated with practically a uniform pressure at each cycle of operations; the ticket strip is fed in such a manner that it is not subjected to strains which would tend to break the strip or tear the strip around the holes in same through which the projections on the feed wheel pass; and as the issued portion of the ticket strip is severed automatically practically as soon as said portion has passed through the slot in the top plate of the machine, there is no danger of a purchaser grabbing his tickets and thus giving the ticket strip a jerk that would cause it to break. In addition to the desirable features above-mentioned my improved machine overcomes the necessity of the operator manipulating anything except the key levers, it is so designed that a fresh ticket strip roll can be inserted quickly thus saving a great deal of valuable time when a number of ticket purchasers are standing at the ticket window, and it is of such simple design that it can be manufactured cheaply.

Having thus described my invention, what I claim as new and desire to secure by Letters Patent is:

1. A ticket-issuing machine provided with a ticket strip feeding mechanism that comprises an actuating member, a spring for moving said member in one direction, a motor-actuated element for moving said member in the opposite direction so as to store up energy in said spring, means for locking said actuating member after said spring has been placed under tension, devices which control or limit the degree of movement of said actuating member, and means under control of the operator for releasing said actuating member and for setting up or arranging in operative position one or the other of said devices.

2. A ticket-issuing machine provided with a ticket strip feeding mechanism that comprises a spring-operated actuating member, a motor-driven element for storing up energy in the spring that operates said member, a locking device for holding said spring under tension, spaced stops which are adapted to be arranged in operative posi-

tion so as to limit the degree of movement of said actuating member, key levers for setting up said stops, and means for tripping or releasing said locking device when one or 5 the other of said key levers is operated.

3. A ticket-issuing machine provided with a ticket strip feeding mechanism that comprises a spring-operated actuating member, a motor-driven element for storing up energy in the spring that operates said member, a locking device for holding said spring under tension, spaced stops which are adapted to be arranged in operative position so as to limit the degree of movement of said 10 actuating member, key levers for setting up said stops, means for tripping or releasing said locking device when one or the other of said key levers is operated, and a cutting mechanism which automatically severs the 15 issued portion of the ticket strip. 20

4. A ticket-issuing machine provided with a ticket strip feeding mechanism that comprises a feed shaft, a feed wheel, a pawl and ratchet mechanism for transmitting movement from said shaft to said wheel, an actuating member for rotating said feed shaft forwardly and rearwardly, resilient means for moving said actuating member in one direction, a motor-driven element for 25 moving said actuating element in the opposite direction so as to store up energy in said spring, and means under control of the operator for limiting the degree of forward movement that said actuating member 30 imparts to said feed shaft. 35

5. A ticket-issuing machine provided with a ticket strip feeding mechanism that comprises a feed shaft, a feed wheel, a pawl and ratchet mechanism for transmitting movement from said shaft to said wheel, an actuating member for rotating said feed shaft forwardly and rearwardly, resilient means for moving said actuating member in one direction, a motor-driven element for moving 40 said actuating element in the opposite direction so as to store up energy in said spring, devices which limit the degree of forward movement that said actuating member imparts to said feed shaft, means for 45 automatically locking said actuating member after said spring has been placed under tension, and means under control of the operator for positioning said devices and for releasing the actuating member from said locking means. 50

6. A ticket-issuing machine provided with a ticket strip feeding mechanism that comprises a feed shaft, a feed wheel, a pawl and ratchet mechanism for transmitting movement from said shaft to said wheel, an actuating member for rotating said feed shaft forwardly and rearwardly, resilient means for moving said actuating member in one direction, a motor-driven element for moving 60 said actuating element in the opposite direction so as to store up energy in said spring, devices which limit the degree of forward movement that said actuating member imparts to said feed shaft, means for 65 automatically locking said actuating member after said spring has been placed under tension, and means under control of the operator for positioning said devices and for releasing the actuating member from said locking means. 70

7. A ticket-issuing machine provided with a ticket strip feeding mechanism that comprises a feed shaft, a flexible actuating member coöperating with a toothed member on said feed shaft, a spring connected to said actuating member for moving it in one direction, a motor-driven element for moving said actuating member in the opposite direction so as to store up energy in said spring, and a plurality of stops which are adapted to be positioned by the operator so as to limit the degree of movement of said actuating member when it is moving under the influence of said spring. 75

8. A ticket-issuing machine provided with a ticket strip feeding mechanism that comprises a feed shaft, a flexible actuating member coöperating with a toothed member on said feed shaft, a spring connected to said actuating member for moving it in one direction, a motor-driven element for moving said actuating member in the opposite direction so as to store up energy in said spring, and a plurality of spaced stops for limiting the degree of movement of said actuating member under the influence of said spring, means for automatically locking said actuating member after said spring has been placed in tension, a plurality of spaced stops for limiting the degree of movement of said actuating member under the influence of said spring, and key levers for positioning said stops and for tripping said locking means. 80 85

9. A ticket-issuing machine provided with a ticket strip feeding mechanism that comprises a feed shaft, an actuating member coöperating with a toothed member on said feed shaft, a spring for moving said actuating member in one direction, a motor-driven element for moving said actuating member in the opposite direction so as to store up energy in said spring, a plurality of movable stops for limiting the degree of movement of said actuating member in one direction, key levers for setting up said stops or arranging them in operative position, means for automatically locking said stops after they have been positioned, and means for releasing said stops and causing them to return to inoperative position after they have performed their function. 90 95 100 105

10. A ticket-issuing machine provided with a ticket strip feeding mechanism that comprises a feed shaft, an actuating member coöperating with a toothed member on said feed shaft, a spring for moving said actuating member in one direction, key levers for setting up said stops or arranging them in operative position, means for automatically locking said stops after they have been positioned, and means for releasing said stops and causing them to return to inoperative position after they have performed their function. 110 115 120 125 130

feed shaft, a spring for moving said actuating member in one direction, a motor-driven element for moving said actuating member in the opposite direction so as to store up 5 energy in said spring, a plurality of stops for arresting the movement of said actuating member under the influence of said spring, key levers for positioning said stops, and means for causing said stops to remain 10 in operative position until said motor-driven element acts upon said actuating member and thereafter to return automatically to in-operative position.

11. A ticket-issuing machine provided 15 with a ticket strip feeding mechanism that comprises a reciprocating member, a spring for moving said member in one direction, a motor-driven element for moving said member in the opposite direction so as to store 20 up energy in said spring, a plurality of stops arranged adjacent the path of movement of said reciprocating member for limiting the degree of movement of said ticket strip feeding mechanism, means under control of the 25 operator for moving one or the other of said stops into operative position, springs that tend to hold said stops retracted or in an in-operative position, means for locking said stops in operative position, means on said 30 reciprocating member that is adapted to engage a positioned stop and release it from said locking means, and independent means on said reciprocating member for preventing the positioned stop from being completely 35 retracted until a subsequent period in the cycle of operations of the machine when said motor-driven element imparts movement to said reciprocating member.

12. A ticket-issuing machine provided 40 with a ticket strip feeding mechanism that comprises a feed shaft, an actuating means for said feed shaft comprising a spring and a reciprocating member, a plurality of stops arranged in a guiding member adjacent the 45 path of travel of said reciprocating member, key levers for positioning said stops, a notch in each of said stops that co-operates with said guiding member to lock the stop in operative position, springs that tend to retract 50 said stops, a pivotally mounted catch on said reciprocating member provided with a tail that is adapted to engage the positioned stop, and a motor-driven element provided with a catch that co-operates with the pivotally 55 mounted catch on said reciprocating member to impart movement to said reciprocating member in one direction.

13. A ticket-issuing machine provided 60 with a ticket strip feeding mechanism that comprises a feed shaft, an actuating means for said shaft comprising a reciprocating member and a spring for moving said member in one direction, stops under control of the operator for arresting the movement of 65 said reciprocating member, a pivotally mounted catch on said reciprocating member that is adapted to be moved into operative position by engagement with the positioned stop, and a motor-driven element that co-operates with said catch to move said reciprocating member in one direction so as to store up energy in said spring.

14. A ticket-issuing machine provided 70 with a ticket strip feeding mechanism that comprises a feed shaft, an actuating means for said shaft comprising a reciprocating member and a spring for moving said member in one direction, stops under control of the operator for arresting the movement of said reciprocating member, a pivotally mounted catch on said reciprocating member that is adapted to be moved into operative position by engagement with the positioned stop, a motor-driven element that co-operates with said catch to move said reciprocating member in one direction so as to store up energy in said spring, and a device on 75 said reciprocating member for preventing the positioned stop from being completely retracted after it has been engaged by the catch on said reciprocating member.

15. A ticket-issuing machine provided 80 with a ticket strip feeding mechanism that comprises a feed shaft, a flexible actuating member passing over a toothed member on 85 said feed shaft, a spring connected to one end of said actuating member, a reciprocating bar connected to the opposite end of said actuating member, a stationary stop and a plurality of stops arranged adjacent the path of travel of said bar, means under control of the operator for positioning said movable stops, a pivotally mounted catch on 90 said bar adapted to be moved into an operative position by engagement with one or the other of said stops, and a motor-driven element provided with means for engaging the catch on said reciprocating bar and retracting it so as to store up energy in said spring.

16. A ticket-issuing machine provided 95 with a ticket strip feeding mechanism that comprises a horizontally disposed feed shaft arranged under the top plate of the machine, a flexible actuating member passing over a sprocket-wheel on said shaft, a spring for 100 moving said actuating member in one direction, a motor-driven element for moving said actuating member in the opposite direction, a plurality of stops for arresting the movement of said actuating member under the influence of said spring, a locking lever co-operating with a notched disk on said feed shaft, and key levers provided with depending arms for positioning said stops and for tripping said locking lever.

17. A ticket-issuing machine provided 110 with a ticket strip feeding mechanism that comprises a horizontally disposed feed shaft arranged under the top plate of the machine, a flexible actuating member passing over a 115 sprocket-wheel on said shaft, a spring for moving said actuating member in one direction, a motor-driven element for moving said actuating member in the opposite direction, a plurality of stops for arresting the movement of said actuating member under the influence of said spring, a locking lever co-operating with a notched disk on said feed shaft, and key levers provided with depending arms for positioning said stops and for tripping said locking lever.

sprocket-wheel on said shaft, a spring for moving said actuating member in one direction, a motor-driven element for moving said actuating member in the opposite direction, a plurality of stops for arresting the movement of said actuating member under the influence of said spring, a locking lever coöperating with a notched disk on said feed shaft, key levers provided with depending arms for moving said stops into operative position, and means connected to said locking lever and arranged in such a manner that it will be engaged by the depending arm of the key lever that is actuated and thus trip said locking lever.

18. A ticket-issuing machine provided with a ticket strip feeding mechanism that comprises a horizontally disposed feed shaft arranged under the top plate of the machine, a flexible actuating member passing over a sprocket-wheel on said shaft, a spring for moving said actuating member in one direction, a motor-driven element for moving said actuating member in the opposite direction, a plurality of stops for arresting the movement of said actuating member under the influence of said spring, a locking lever coöperating with a notched disk on said feed shaft, key levers provided with depending arms for moving said stops into operative position, means connected to said locking lever and arranged in such a manner that it will be engaged by the depending arm of the key lever that is actuated and thus trip said locking lever, a severing mechanism for the ticket strip comprising a movable cutting member, a rock arm loosely mounted on the feed shaft and operatively connected to said movable cutting member, a spring for moving said rock arm in one direction, and means on the feed shaft for moving said rock arm in the opposite direction so as to actuate said cutting member.

19. A ticket-issuing machine provided with a ticket strip feeding mechanism that comprises a feed shaft, a ticket strip severing mechanism comprising a stationary cutting member and a movable cutting member, a rock arm for actuating said movable cutting member, means for causing said rock arm to open up or separate said cutting members when the feed shaft moves in one direction, means on the feed shaft that is adapted to engage said rock arm so as to positively actuate said movable cutting member when the feed shaft moves in the opposite direction, said movable cutting member being pivotally connected to said stationary cutting member, and removable fastening devices which retain both of said cutting members in operative position under the top plate of the machine.

20. A ticket-issuing machine provided with a ticket strip feeding mechanism that comprises a feed wheel and a feed shaft, in-

dependent means for rotating said feed shaft in opposite directions, a pawl and ratchet mechanism for transmitting movement from said shaft to said wheel, and means for preventing said feed wheel from overthrowing or moving beyond a certain position.

21. A ticket-issuing machine provided with a ticket strip feeding mechanism that comprises a feed wheel and a feed shaft, independent means for rotating said feed shaft in opposite directions, a pawl and ratchet mechanism for transmitting movement from said shaft to said wheel, means for preventing said feed wheel from overthrowing or moving beyond a certain position, consisting of a stationary locking member and a movable locking member, one of said members having a projection that co-operates with notches in the other member.

22. A ticket-issuing machine provided with a ticket strip feeding mechanism that comprises a feed wheel having devices for engaging the ticket strip, a spring for causing said wheel to feed the ticket strip forwardly, a motor-actuated element for storing up energy in said spring, a locking device which automatically locks said feeding mechanism after the spring has been placed in tension, and means under control of the operator for tripping said locking device and for limiting the degree of movement that said feed wheel imparts to said ticket strip.

23. A ticket strip feeding mechanism for a ticket-issuing machine consisting of a feed wheel, a feed shaft, means for transmitting motion from said shaft to said wheel, a spring for rotating said shaft in one direction, a motor for storing up energy in said spring and simultaneously rotating said shaft in the opposite direction, a stationary ring provided with notches, and a spring-actuated pawl on said feed wheel that co-operates with the notches in said ring to prevent the feed wheel from overthrowing.

24. A ticket strip feeding mechanism for ticket-issuing machines consisting of a feed wheel, a feed shaft, a toothed wheel on said shaft that co-operates with a pawl on said feed wheel, means for rotating said shaft in opposite directions, a stationary ring arranged adjacent said wheel and provided with notches, and a spring-actuated locking dog on said wheel provided with a projection that enters said notches and thus prevents the feed wheel from overthrowing.

25. A ticket strip feeding mechanism for ticket-issuing machines consisting of a feed wheel, a feed shaft, a toothed wheel on said shaft that co-operates with a pawl on said feed wheel, means for rotating said shaft in opposite directions, a stationary ring arranged adjacent said wheel and provided with notches, a spring-actuated locking dog on said wheel provided with a projection

that enters said notches and thus prevents the feed wheel from overthrowing, and means on said dog that is adapted to co-operate with the toothed wheel on said shaft 5 for restoring the feed wheel to the position in which it should have stopped in case it accidentally moves beyond a certain point.

26. In a ticket-issuing machine, a feed wheel, an arc-shaped guard arranged adjacent 10 cent said wheel for supporting the ticket strip with which the feed wheel co-operates, a removable cover plate that closes an opening in the top plate of the machine, and devices on said cover plate that co-operate with 15 said guard to form a guideway for the ticket strip.

27. A ticket-issuing machine provided with a ticket strip feeding mechanism that comprises a feed wheel and mechanism for 20 rotating said feed wheel forwardly, a spring-actuated pivotally mounted device arranged adjacent one side of said wheel, said device being provided with a portion that bears against the under side of said ticket strip 25 and thus normally holds said device in an inoperative position, and means on said device that is adapted to co-operate with a shoulder or projection on one side of the feed wheel to arrest the forward movement of said feed 30 wheel after the last ticket of the strip has been issued.

28. A ticket-issuing machine provided with a roller that forms a support for the lower side of the ticket strip roll, a pivotally mounted resilient arm provided with means that projects into the spool on which 35 said ticket strip is wound, and means for feeding said ticket strip forwardly.

29. A ticket-issuing machine provided 40 with a roller that forms a support for the ticket strip roll, a pivotally mounted resilient arm provided with means for engaging the spool on which said ticket strip is wound, a spring-actuated feed wheel for 45 feeding said strip forwardly, and means for automatically taking up the slack in said ticket strip.

30. In a ticket-issuing machine, a roller that acts as a support for a ticket strip 50 roller, a feed wheel for the ticket strip, a feed shaft, means for transmitting movement from said shaft to said wheel, means for actuating said shaft, and means for imparting movement to the roller on which 55 said ticket strip roll rests.

31. A ticket-issuing machine provided with a ticket strip feeding mechanism that comprises a feed wheel for moving the ticket strip forwardly, a spring-actuated shaft for 60 imparting forward movement to said wheel, a motor for storing up energy in said spring, means for holding said spring under tension so that it will be in a condition to actuate 65 said shaft on the next cycle of operations of the machine, and means adapted to be actu-

ated by the operator for determining the number of tickets to be issued and for releasing the spring from said holding means.

32. A ticket-issuing machine provided with a ticket strip feeding mechanism that 70 comprises a motor, means for causing said motor to become operative automatically after the feeding mechanism has been set in operation and thereafter to cease automatically to operate, and means under control of 75 the operator for determining the number of tickets that are to be issued and for setting said feeding mechanism in action by a single operation.

33. A ticket-issuing machine provided 80 with a ticket strip feeding mechanism that comprises a spring for actuating said mechanism and an electric motor for storing up energy in said spring, and automatic means for causing said motor to operate for a 85 short period during each cycle of operations of the machine and then become inoperative after said spring has been placed under tension.

34. A ticket-issuing machine provided 90 with a ticket strip feeding mechanism that comprises an electric motor, a switch for controlling the circuit that energizes said motor, and a movable member forming part 95 of said feeding mechanism that co-operates with said switch to open and close said circuit automatically during each cycle of operations of the machine.

35. A ticket-issuing machine provided 100 with a ticket strip feeding mechanism that comprises a spring-operated actuating member, a locking device which normally holds the spring of said member under tension, means for tripping said locking device, a 105 motor for storing up energy in said spring, and means for automatically closing the circuit that energizes said motor when said locking device is tripped and thereafter open said circuit after said spring has been placed under tension.

36. A ticket-issuing machine provided 110 with a ticket strip feeding mechanism that comprises a spring-operated reciprocating member, an electric motor, an element operated by said motor for moving said reciprocating member in one direction so as to store up energy in the spring that operates same, a switch arranged in the circuit that energizes said motor, and a movable contact that is actuated automatically by said reciprocating member so as to open and close said circuit.

37. A ticket-issuing machine having a top 115 plate provided with a ticket slot, means for supporting a ticket strip roll under said top plate, a spring-actuated feeding mechanism for feeding the ticket strip upwardly through said slot, key levers arranged under said top plate for controlling the movement of said feeding mechanism, finger-pieces on 120 125

130

said key levers that project upwardly through said top plate, a cutting mechanism arranged under the top plate for severing said ticket strip, and a motor-driven means 5 for actuating said cutting mechanism and for storing up energy in the spring that operates said feeding mechanism.

38. A ticket-issuing machine provided with a ticket strip feed wheel having projections that enter openings in the ticket strip, a feed shaft, a pawl and ratchet mechanism for transmitting movement from said feed shaft to said feed wheel, a device on the feed wheel that co-operates with a stationary 10 member for preventing the feed wheel from overthrowing, a sprocket chain passing over a sprocket wheel on the feed shaft, a spring connected to said chain for moving the feed shaft forwardly, a motor-driven element for 15 moving said chain in the opposite direction so as to store up energy in said spring, stops that are adapted to be set up so as to limit the degree of movement imparted to said feed shaft by said spring, a device for locking 20 said feed shaft after said spring has been placed under tension, and key levers for tripping said locking device and for setting up said stops.

39. A ticket-issuing machine provided 30 with a ticket strip feed wheel having projections that enter openings in the ticket strip, a feed shaft, a pawl and ratchet mechanism for transmitting movement from said feed shaft to said feed wheel, a device on the feed wheel that co-operates with a stationary 35 member for preventing the feed wheel from overthrowing, a sprocket chain passing over a sprocket wheel on the feed shaft, a spring connected to said chain for moving the feed shaft forwardly, a motor-driven element for moving said chain in the opposite direction so as to store up energy in said spring, stops that are adapted to be 40 set up so as to limit the degree of movement imparted to said feed shaft by said spring, a device for locking said feed shaft after said spring has been placed under tension, key levers for tripping said locking device and for setting up said stops, a severing 45 mechanism for said strip comprising a movable cutting member, a spring for moving said cutting member in one direction so as 50

to permit the ticket strip to move past same, means on the feed shaft for positively actuating said cutting member so as to sever the strip, and means for recording the number of tickets that issue from the machine. 55

40. In a ticket-issuing machine, a rotatable support for sustaining a ticket strip roll, a feed wheel for feeding the strip forwardly, and means for rotating said support so as to aid said feed wheel to feed the ticket strip. 60

41. In a ticket-issuing machine, a ticket strip feeding mechanism, devices for determining the degree of movement of said feeding mechanism, key levers for positioning said devices, and unyielding means for restoring said key levers to their normal raised position, after they have been 65 depressed. 70

42. In a ticket-issuing machine, a ticket strip feeding mechanism, devices for determining the degree of movement of said feeding mechanism, key levers for positioning said devices, and a positively actuated means that operates at each cycle of operations of the machine for restoring the key levers to their normal raised position after 75 they have been depressed. 80

43. A ticket-issuing machine comprising a ticket strip feeding mechanism, a cutting mechanism, means under control of the operator for causing said feeding mechanism to become operative, and a motor-driven element that operates automatically to restore the feeding mechanism and also to actuate the cutting mechanism so as to sever the issued portion of the ticket strip. 85

44. A ticket-issuing machine provided 90 with a ticket strip feeding mechanism that comprises a feed shaft, key levers for controlling said mechanism, and means operated by said feed shaft for positively restoring the key levers after they have been 95 actuated by the operator.

In testimony whereof, I hereunto affix my signature in the presence of two witnesses, this eighteenth day of July 1912.

WILLIAM L. SULLIVAN.
